UNITED STATES PATENT OFFICE.

LOUIS E. WALKINS, OF SPRINGFIELD, MASSACHUSETTS, ASSIGNOR OF ONE-HALF TO FRANCKE W. DICKINSON, OF SAME PLACE.

PROTECTIVE APPLIANCE FOR ELECTRIC RAILWAYS.

SPECIFICATION forming part of Letters Patent No. 600,564, dated March 15, 1898.

Application filed July 17, 1897. Serial No. 644,917. (No model.)

To all whom it may concern:

Be it known that I, LOUIS E. WALKINS, a citizen of the United States, and a resident of Springfield, in the county of Hampden and 5 State of Massachusetts, have invented certain new and useful Improvements in Protective Appliances for Electric Railways, of which the following is a specification.

This invention relates to protective devices 10 for electric railways wherein a third-rail conductor is employed comprised in the power-circuit, the object of the protective devices being to prevent a person who may be walking on or crossing the railway from coming 15 in contact with the intermediate conductor-rail, whereby he might receive a shock, the said appliances being so constructed and sustained that while effectually serving the purposes for which they are primarily intended 20 they and their conjunctive equipments will not constitute a catch-pocket or trough for water, snow, dirt, or other matter, but will effectually shed the same or readily allow of 25 the same being shed away from the rail; and the invention consists in the third-rail conductor, its support or exposed conduit above 30 the level of the bed-trackway, and the protective appliances ranging along parallel with and in proximity to the third rail, and yet so 35 as not to obstruct the entrance of the shoe or underrunning trolley upon the third-rail conductor, said protective appliances being sustained on separate pillars rising at either side of the rail support or bed.

35 The improvement is fully illustrated in the accompanying drawings, in which—

Figure 1 is a plan view of the third-rail conductor, the supports and housing therefor, and the guard-rails, which are insulated 40 from, but supported in proximity to, the third-rail conductor. Fig. 2 is a cross-sectional view of the same on line 2 2.

In the drawings, A represents the "third-rail" conductor, as termed, it being understood as being a rail located along and above the road-bed between and parallel with the usual car-track rails. (Not shown.)

B represents a trough-like upwardly-open support or conduit for the conductor-rail, 45 which I prefer to have of insulating material,

such as anaglypta or vulcanite, the rail being supported therein and confined in any suitable manner and by any suitable means.

a a represent current-wires connecting the third rail and bonded thereto, and b represents a filling substance of insulating material in the conduit covering and inclosing the base and neck of the rail, leaving the tread portion only thereof exposed. The conduit B is supported on cross-ties or tie-supported beams 55 on the railway and has the angle-braces d d for maintaining it stable.

C C represent the protector guard-rails, the same ranging parallel with each other and with the rail, above the level of the rail, and 60 being supported by the pillars ff, rising above the opposite edges of the conduit at suitable intervals—as, for instance, every four or five feet.

In practice it is desirable to have the guard-rails C C separated by a space between their inner edges of about four inches, which is ample for the passage of the shoe G onto the rail A, and yet is such that the rail is substantially bridged, so that the foot will not 75 come upon the rail.

The filling b and the top edges of the conduit B, which constitute the support and "bed" for the third rail, are downwardly and outwardly inclined from the rail, as seen at 80 g, whereby gravel, dirt, or snow or other obstruction will have a tendency to be shed from the rail or the surface at the base thereof.

I claim—

1. In an electric railway, the combination 85 with the "third-rail" conductor and a support and bed for said rail constructed to partially inclose the rail and having the upper surface thereof inclining from near the tread portion of the rail outwardly and downwardly 90 at each side thereof, of separated supports rising above the bed at intervals along, at either side of the rail, and the guard-rails sustained in separation and parallelism above the rail-top, on said supports, substantially 95 as and for the purposes described.

2. In an electric railway the combination 100 with the "third-rail" conductor, the trough-conduit in which it is centrally supported, the separated pillars rising above the sides of

the trough-conduit, the guard-rails supported in parallelism by said pillars, and the filling *b* in said trough, the top of which together with the top edges of the trough-conduit are 5 downwardly and outwardly inclined, as described for the purpose set forth.

In testimony that I claim the foregoing as

my invention I have signed my name, in presence of two witnesses, this 10th day of June, 1897.

LOUIS E. WALKINS.
